UNITED STATES PATENT OFFICE.

JOHN H. HANKINSON, OF NEW YORK, N. Y.

DESIGN FOR A TILE.

SPECIFICATION forming part of Design No. 17,020, dated December 7, 1886.

Application filed October 21, 1886. Serial No. 216,910. Term of patent 7 years. Patented in England July 6, 1886, No. 51,873.

To all whom it may concern:

Be it known that I, JOHN H. HANKINSON, a citizen of the United States, residing at New York, in the county and State of New York, have invented and produced a new and original Design for Tiles for Facings, Hearths, &c., of which the following is a specification, reference being had to the accompanying drawings, forming part thereof.

10 Figure 1 is a face or top view of my newly-designed tile, and Fig. 2 is a transverse vertical section thereof, taken at line $x\ x$ of Fig. 1.

15 Tiles for floors, hearths, and facings have heretofore been made with rectangular edges, and presented the appearance of a continuous plane surface at their joints when placed together as in a floor or facing.

The characteristic feature of my design consists in the rounded-off face corners of the tiles, and presents the view of a convex chamfered 20 border, B, the lower edge corners remaining flush. The rounded surface or border leaves no irregular surface at the line of connection between the plane face A of the tile and the rounded upper corner or outline. 25

I claim and desire to secure by Letters Patent—

The design for ornamental tiles herein shown and described, the same consisting of the plane surface A and rounded corners or borders B. 30

JOHN H. HANKINSON.
